UNITED STATES PATENT OFFICE

2,428,492

AGITATING MACHINE

John Haller, Northville, Mich.

Application May 13, 1944, Serial No. 535,469

3 Claims. (Cl. 259—67)

1

The present invention relates to improvements in agitating machines, and more particularly to a machine for mixing paint and other viscous material.

The primary object of the invention is to provide an agitating machine which is adapted to accommodate a plurality of receptacles to facilitate the mixing of a large number of different paints and viscous materials simultaneously.

Another object of the invention is to provide an agitating machine constructed and arranged so as to permit the easy removal and installation of the receptacles and to provide each receptacle with an individual stirrer operated from a common source of power.

Another object of the invention is to provide an agitating machine of the above-mentioned character having means for removably receiving a plurality of paint containers and to provide means for locking the containers in position during the mixing operation.

Another object of the invention is to provide an agitating machine in which the stirrer is carried by a removable cover adapted to be locked in position so as to confine the contents of the receptacles and prevent the same from splashing during the agitating operation.

Another object of the invention is to provide an agitating machine including a series of tiers for receiving a plurality of receptacles so that the stirrer mounted in the cover of the receptacle may be driven by an endless chain in such a manner as to permit the easy positioning of the receptacle and removal thereof from the agitating machine and yet permit the endless chain to effectively drive the stirrers of a plurality of containers simultaneously without requiring numerous mechanical connections between the endless sprocket chain and the various stirrer mechanisms for the receptacle.

Other objects and advantages of the invention will become apparent during the course of the following description of the accompanying drawings, wherein:

Figure 1 is a longitudinal cross sectional view of the agitating machine illustrating the manner in which a plurality of receptacles may be positioned therein for the purpose of agitating the contents thereof;

Figure 2 is a horizontal cross sectional view taken on line 2—2 of Figure 1 looking in the direction of the arrows and partly broken away to illustrate the drive mechanism for the several containers;

Figure 3 is a vertical cross sectional view taken

2

on line 3—3 of Figure 1 looking in the direction of the arrows showing the drive mechanism for effectively driving the stirrers of a plurality of receptacles when positioned in the agitating machine;

Figure 4 is an enlarged vertical cross sectional view illustrating various structural details of the receptacle cover and stirrer therefor;

Figure 5 is a horizontal cross sectional view taken on the irregular line 5—5 in Figure 4 looking in the direction of the arrows and illustrating the manner in which the receptacle is clamped in position and certain features of the receptacle cover; and

Figure 6 is a vertical cross sectional view taken on the zigzag line 6—6 of Figure 5 looking in the direction of the arrows illustrating the closure member for the cover spout.

In the drawings, wherein for the purpose of illustrating the invention like reference characters will be employed to designate like parts throughout, the reference character 10 will generally indicate a base having a depending flange 11 extending downwardly from the front, rear and ends thereof. Secured to the base 10 and welded to the depending flange 11 at the marginal edge thereof is a pair of uprights 12 having inwardly directed flanges 13 at each vertical edge thereof to form the side walls of a cabinet structure of any desired height. The upper ends of the uprights 12 are connected by a cover plate 14 having a marginal depending flange 15 extending along sides and ends thereof which embrace the upper ends of said side walls 12 and are adapted to be secured thereto by welding or the like at various points of contact.

Mounted within the cabinet structure above-described and extending between the uprights 12 is a series of horizontal shelves 16 and 17 and said shelves are provided with marginal depending flanges 18 and 19 respectively for abutting said side walls 12 and flanges 13 thereof so that portions of the depending flanges 18 and 19 may be welded or otherwise secured to the side walls 12 of the cabinet structure.

Mounted on the base 10 and shelf 16 is a plurality of receptacle-supporting platforms generally indicated by the reference character 20 and since each of the platforms is identical in structure, a description of one will suffice for all. Generally, the platform 20 comprises a disc-like base 21 of sufficient diameter to support a container represented by the reference character 22. Depending from the disc-like platform 21 at diametrically opposed points thereon are bracket

extensions 23 which depend downwardly and terminate in foot portions 24 for being fastened or anchored to the base 10 or shelf 16 by means of bolts or the like as at 25 extending through openings 26 in said foot portions with the free ends projecting through suitable openings 27 in said base 10 and shelf 16. A nut 28 is threaded on the bolt for securely clamping and holding the platforms 20 in position. The platforms 20 are provided with upwardly extending circumferentially spaced receptacle-engaging members 30 and a camming cam member 31 is rotatably mounted in an extension 32 on the disc-like platform 21 for camming the base of the receptacle against the upstanding can-engaging members 30. The cam 31 is secured to one end of the shaft 33 which is rotatably mounted in a bore 34 of said extension 32 and a control finger piece 35 is secured to said shaft so as to rotate the same and move the cam 31 into engagement with the can base 32. A finger piece 36 is formed on the operating member 35 to facilitate the easy rotation of the shaft 33 and the engagement of the cam 31 with the can base.

As indicated in Figure 1, the cans 22 are uniform in size and comprise a bottom wall 37 secured to a cylindrical wall 38 by bending the edge of the bottom wall 37 over the lower edge of the cylindrical wall 38 as at 39, and forming a sealing engagement therewith. The top edge of the cylindrical wall 38 is provided with an inwardly extending flanged member 40 which has its marginal edge 41 bent over and pressed into sealing contact with said upper edge of the cylindrical wall 38. The receptacle 22 may represent a conventional paint can or container of other viscous material, the contents of which are to be stirred or mixed and as is usual in cans and receptacles of this type, the inwardly directed flange 40 is offset as at 42 and terminates in an upwardly and downwardly extending flange portion 43 to provide a sealing lip for the usual can cover (not shown).

The usual can cover is adapted to be replaced by a closure member 44 of disc-like shape having a downwardly depending peripheral flange 45 return bent as at 46 to provide a rounded contact surface 47 for being received in the offset portion 42 of the inwardly extending flange 40. A central opening 48 is formed in the closure member 44 and located in said opening is a bearing block 49 secured in place by being spun as at 50. A washer 51 is interposed between the top wall of the closure member and the spun portion 50 of the bearing member 49 to additionally seal and lock the bearing member 49 within the closure member 44. The bearing member 49 is provided with a longitudinal bore 52 for receiving the rotary shaft 53 and is provided with a reduced threaded portion 54 for receiving a packing gland nut 55. A quantity of sealing and packing material 56 is mounted in the packing gland nut 55 so as to seal the rotary shaft 53 against liquid escape. Each of the rotary shafts 53 is provided with two or more radially extending paddles 57 which are mounted at right angles to one another and said paddles are provided with central depressed portions 58 for receiving the contour of the shaft 53 and facilitate the welding of said paddles in position. Radially extending ribs 59 are formed in the paddles 57 to reinforce the same throughout their length.

The upper end of each rotary shaft 53 projects through the bearing member 49 and has secured thereto a sprocket wheel 60 by means of a trans-

verse locking pin 61 and said sprocket wheel is provided with a series of sprocket teeth 62 for drivingly engaging a sprocket chain in a manner which will be hereinafter more fully described.

The removable closure or cover member 44 is provided with a pair of diametrically arranged openings 63 in which are fitted bearing members 64 for receiving a rotatable stub shaft 65. Cam clamping discs 66 are secured to the lower end of said shaft 65 and said clamping discs are provided with cam surfaces 67 adapted to engage the underside of the offset portion 42 of the inwardly extending flange 40 and thereby secure the cover member 44 in place. A collar 68 is secured to the upper end of each stub shaft 65 and is provided with a finger piece 69 to facilitate rotation of said shaft and cam disc 66 to thereby securely lock the cover member 44 in position.

Also mounted in the cover plate 44 is a pouring spout 70 having an annular flange 71 which may be welded to the cover member 44 as indicated in Figure 6. The upper end of the pouring spout 70 is provided with a sleeve 72 having oppositely extending flanges 73 and 74 to provide a base for a swinging closure plate 75. A pivot pin 76 is provided for pivotally attaching the closure plate 75 to the flange 73 and a spring clip 77 is formed integral with the opposite flange member 74 for engaging over said closure plate 75 when the same is in its closed position and securely hold the closure plate against the upper edge of the pouring spout 70. A finger piece 78 is formed integral with the closure plate 75 to facilitate the opening and closing thereof when it is desired to pour the contents of said can 22 into a plurality of other receptacles.

The drive mechanism for the various stirrers or agitating blades 57 comprises a vertical shaft 79 rotatably mounted in suitable bearings 80 and 81 in the various shelves 16 and 17 respectively and the upper end of said shaft extends into a gear housing 83 formed integral with the bearing 81 and is provided with a worm wheel 84 shown in dotted lines in Figures 1 and 2. The gear housing 83 is formed with an extension 85 into which extends and is rotatably mounted a drive shaft 86 (Figure 2), and said drive shaft is provided with a worm 87 drivingly engaging the worm wheel 84 on the upper end of the rotary shaft 79. A motor 88 has its base 89 fastened to the shelf 17 by means of bolts or the like 90 and the armature shaft 91 of said motor is connected to the worm shaft 86 by means of a suitable coupling element 92. Mounted on the shaft 79 at spaced apart locations, is a series of sprocket wheels 94 the hubs of which at 95 are secured in place by transverse locking pins 96. Mounted on the under side of the shelves 16 and 17 and secured thereto by screws or the like 97 is a bearing support 98 and said bearing support is provided with a sliding block 99 movable to and fro within said guide 98. The bearing block 99 is provided with screw-threaded openings 100 for receiving a sprocket wheel shaft 101 upon which is mounted a sprocket wheel 102 in horizontal alignment with the sprocket wheels 94. A nut 103 is threaded on the lower end of the sprocket shaft 101 to securely hold the sprocket 102 in position but permit free rotation thereof on said shaft. Mounted in the bearing guide 98 is a coil spring 104 having one end abutting the guide and the other end abutting the gauge block 99 so as to urge said block in a direction opposed to the sprocket wheels 94.

Sprocket chains 106 and 107 are trained over

the horizontally aligned sprocket wheels 94 and 102 in such a manner as to be positioned in driving engagement with the sprocket wheels 60 mounted on the upper ends of the rotary shafts 53 of the various agitating stirrers in said receptacles 22. In order to hold and guide the sprocket chains 106 and 107 in driving engagement with the sprocket wheels 60, a series of idle sprockets 108 are mounted on shafts 109 which are bolted to the shelves 16 and 17 by means of nuts or the like 110 and spacing studs 111 are provided for receiving said shafts and maintaining the idle sprockets in spaced relation from the bottom walls of the respective shelves 16 and 17. The idle sprockets are positioned in back of the sprocket chain 107 so that when the receptacles 22 with the cover plates 44 are positioned on the platforms 20, the sprockets 60 of the stirrers will be pressed into engagement with the sprocket chain 107 and into driving engagement therewith. As the receptacles are inserted and removed, the sliding bearing block 99 and sprocket wheel 102 will move inwardly and outwardly to compensate for the lateral chain movement and thereby maintain the sprocket chain 107 in tight driving engagement with said sprocket 60 to cause the rotation of the stirrers in the various receptacles 22.

In operation, the motor 83 is connected to a suitable source of current so that the drive shaft 86, worm 87 and vertical drive shaft 79 will be driven at a constant rate of speed. Upon rotation of the vertical drive shaft 79, the sprocket chains 106 and 107 will be driven in the same direction and the receptacles 22 may be positioned on a platform 20 with the closure member 44 in place thereon so that the sprocket wheels 60 on the upper ends of rotary shafts 53 in said closure members will be drivingly engaged by the sprocket chains 106. It is to be noted that receptacles 22 may be inserted and removed from the agitating machine on opposite sides thereof with ease and facility and that the stirrers of the various receptacles will be operated in unison. By reason of the unique construction, one or more of the receptacles 22 may be removed from the agitating machine without disturbing the agitating operation of the remaining receptacles and that receptacles 22 of various sizes may be employed by altering the size of the closure member 44 and the paddles 57 and employing rotary shafts 53 of the same size as used for other receptacles.

In inserting and removing cans or receptacles 22, it is simply necessary to operate the finger piece 36 of the clamping cam 31 so as to move the cam away from the base 37 of the receptacle 38 and permit the removal of the same away from the base-engaging lugs or members 30. The cabinet structure may be of any height desired with as many shelves and sprocket chains as needed to accommodate a large number of receptacles 22 fitted with the stirrers 53 and 57 with the sprockets 60 thereof positioned for engagement with the sprocket chains 106 and 107.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

1. A quick-detachable stirring machine for stir- 75

ring materials without removing them from the commercial open-topped closed-bottomed containers in which they are sold, said machine comprising a frame, a pair of sprockets spacedly and 5 rotatably mounted on said frame, a power source drivingly connected to one of said sprockets, an endless sprocket chain meshing with said sprockets, a cover structure including a quickly-removable closure member fitting over the open top 10 of each container, a vertical shaft journaled solely in said cover structure and extending downward therefrom into said container, an agitator mounted on said shaft, said shaft and agitator being spaced from said container and free from 15 direct contact therewith, a driven sprocket mounted on the upper portion of said shaft externally of said container, and means for holding said agitator sprocket positioned in pressing engagement against said sprocket chain whereby 20 to enable quick engagement and disengagement of said agitator sprocket from said sprocket chain.

2. A quick-detachable stirring machine for stirring materials without removing them from the commercial open-topped closed-bottomed 25 containers in which they are sold, said machine comprising a frame, a pair of sprockets spacedly and rotatably mounted on said frame, a power source drivingly connected to one of said sprockets, an endless sprocket chain meshing with said 30 sprockets, a cover structure including a quickly removable closure member fitting over the open top of each container, a vertical shaft journaled solely in said cover structure and extending downward therefrom into said container, an agitator 35 mounted on said shaft, said shaft and agitator being spaced from said container and free from direct contact therewith, a driven sprocket mounted on the upper portion of said shaft externally of said container, means for holding said 40 agitator sprocket positioned in pressing engagement against said sprocket chain whereby to enable quick engagement and disengagement of said agitator sprocket from said sprocket chain, said sprocket chain being slackly mounted on 45 said sprockets, and take-up mechanism disposed adjacent said agitator sprocket on the opposite side of said sprocket chain from said agitator sprocket whereby to cause a slack portion of said sprocket chain to partially encircle said agitator sprocket pressed thereagainst while taking up a portion of said slack.

3. A quick-detachable stirring machine for stirring materials without removing them from the commercial open-topped closed-bottomed 55 containers in which they are sold, said machine comprising a frame, a pair of sprockets spacedly and rotatably mounted on said frame, a power source drivingly connected to one of said sprockets, an endless sprocket chain meshing with said 60 sprockets, a cover structure including a quickly removable closure member fitting over the open top of each container, a vertical shaft journaled solely in said cover structure and extending downward therefrom into said container, an agitator 65 mounted on said shaft, said shaft and agitator being spaced from said container and free from direct contact therewith, a driven sprocket mounted on the upper portion of said shaft externally of said container, means for holding said 70 agitator sprocket positioned in pressing engagement against said sprocket chain whereby to enable quick engagement and disengagement of said agitator sprocket from said sprocket chain, said sprocket chain being slackly mounted on said

sprocket wheels, and a pair of take-up wheels disposed in spaced relationship substantially on opposite sides of said agitator sprockets and on the opposite side of said sprocket chain from said agitator sprocket whereby to cause a slack portion of said sprocket chain to partially encircle said agitator sprocket pressed thereagainst while taking up a portion of said slack.
